UNITED STATES PATENT OFFICE.

JOHN T. FLIPPEN, SR., OF TRELOW, VIRGINIA, ASSIGNOR OF ONE-HALF TO
JOHN T. FLIPPEN, JR., OF MONARAT, VIRGINIA.

FUMIGATOR.

SPECIFICATION forming part of Letters Patent No. 651,030, dated June 5, 1900.

Application filed April 5, 1899. Renewed May 1, 1900. Serial No. 15,131. (No model.)

To all whom it may concern:

Be it known that I, JOHN T. FLIPPEN, Sr., a citizen of the United States, residing at Tre-
low, in the county of Pittsylvania and State
5 of Virginia, have invented a new and useful
Fumigator, of which the following is a speci-
fication.

The invention relates to improvements in
fumigators.

10 The object of the present invention is to
improve the construction of fumigators and
to provide a simple, inexpensive, and efficient
apparatus adapted for discharging the fumes
of various chemicals and designed to be em-
ployed for impregnating various articles of
15 food with a preservative compound and for
spraying plants with poison for destroying
various forms of insect life.

10 The invention consists in the construction
20 and novel combination and arrangement of
parts hereinafter fully described, illustrated
in the accompanying drawings, and pointed
out in the claims hereto appended.

25 In the drawings, Figure 1 is a perspective
view of a fumigator constructed in accord-
ance with this invention. Fig. 2 is a vertical
sectional view of the same. Fig. 3 is a hori-
zontal sectional view.

30 Like numerals of reference designate cor-
responding parts in all the figures of the draw-
ings.

35 I designates a casing constructed of suit-
able material and preferably rectangular in
section, as illustrated in Figs. 2 and 3 of the
accompanying drawings, and it is provided
near its bottom with a horizontal partition 2,
40 dividing the casing into upper and lower com-
partments. The horizontal partition is pro-
vided with openings 3 for the passage of the
fumes given off by chemicals contained with-
in a receptacle 4, located in the upper com-
partment and adapted to be introduced into
45 and removed from the same by means of a
door 5, which may be of any desired construc-
tion. The receptacle, which may be of any
preferred construction, is supported in an
opening of the horizontal partition, which
50 forms a seat 6 for the receptacle.

Within the casing is arranged a pump 7,
55 adapted to draw the fumes from the upper
casing and discharge them through a tube or

pipe and consisting of a vertical pump well or
casing 9 and a plunger 10, operating through
a perforation of the top of the casing 1. The
plunger consists of a rod provided at its up-
55 per end with a suitable knob or grip 11 and
having a head 12 at its lower end fitting
snugly within and conforming to the configu-
ration of the pump well or casing. The
pump well or casing, which extends from the
60 horizontal partition to the top of the main
casing 1, is preferably rectangular in cross-
section, and when the plunger of the pump is
moved upward the fumes are drawn from the
upper compartment through the openings of
65 the horizontal partition into the pump well or
casing, and they are dispelled through the
discharge-tube 8 by the downward movement
of the plunger.

An inwardly or upwardly opening valve 13
70 is arranged at the lower end of the pump
well or casing, and an outwardly-opening
valve 14 is mounted within a cap 15, to which
the discharge pipe or tube is secured. The
cap 15, which is arranged on the exterior of
75 the main casing 1, is disposed over an open-
ing thereof, and it receives the inner end of
the discharge pipe or tube. The top of the
main casing is provided with a handle 16 to
enable the device to be readily carried.
80

The invention has the following advan-
tages: The fumigator, which is simple and
comparatively inexpensive in construction,
is strong and durable and adapted to be read-
ily operated. It is capable of being used for
85 a variety of purposes and is adapted to dis-
charge the fumes of preservative compounds
on food substances, and it forms a conven-
ient means for spraying plants and the like
with poisoning substances for destroying all
90 forms of insect life. The chemicals or com-
pounds are conveniently arranged within the
removable receptacle, and the fumes are
drawn through the perforations or openings
of the horizontal partition into the pump well
95 or casing on the upstroke of the plunger and
are expelled through the discharge pipe or
tube on the downstroke of the pump. The
lower valve opens automatically to permit
the fumes to enter the pump and the outer
100 valve operates similarly to permit the fumes
to be discharged. While the fumes are be-

ing drawn into the pump the outer valve remains closed to prevent the fumes from being diluted with air before being discharged.

Changes in the form, proportion, size, and 5 the minor details of construction within the scope of the appended claims may be resorted to without departing from the spirit or sacrificing any of the advantages of this invention.

What is claimed is—

- 10 1. A device of the class described comprising a main casing, a horizontal partition arranged within the main casing and provided with perforations and dividing the said main casing into upper and lower compartments, the upper compartment being designed to receive a chemical or a compound, a pump mounted within the casing and extending upward from the horizontal partition and communicating with the lower compartment, said 20 pump being adapted to draw the fumes from the upper compartment through the perforations of the partition into the lower compartment, and a discharge pipe or conduit connected with the pump, substantially as described.
- 25 2. A device of the class described comprising a casing having a door, a partition located below the door and dividing the casing into upper and lower compartments, said par-

tion being provided with openings for the 30 passage of the fumes, a receptacle adapted to be supported by the partition, a pump mounted within the upper compartment of the casing and communicating with the lower compartment, and a discharge pipe or conduit connected with the pump, substantially 35 as described.

3. A device of the class described comprising a main casing, a horizontal partition having openings and arranged within the main 40 casing, said partition dividing the main casing into upper and lower compartments, a pump-casing arranged within the upper compartment and extending from the partition to the top of the main casing, a plunger operating in the pump-casing, a cap mounted on the exterior of the main casing and communicating with the pump-casing, and a discharge pipe or tube connected with the cap, 45 substantially as described. 50

In testimony that I claim the foregoing as my own I have hereto affixed my signature in the presence of two witnesses.

JNO. T. FLIPPEN, SR.
